MEANS FOR PROJECTING TUNING INDICIA

John L. McWeeny, Chicago, Ill.

Application January 16, 1937, Serial No. 120,361

6 Claims. (Cl. 116—124.6)

My invention relates to radio apparatus and particularly to means for projecting the indicia on a tuning dial onto a screen. This invention represents a variation in the construction described and claimed in my copending application, Serial No. 110,461, filed November 12, 1936.

In the application above identified I have disclosed a construction in which a tuning dial is employed having concentric series of station designations, the dial being so constructed that light may be projected therethrough. Mounted adjacent to the dial or disc is a source of light adapted to project its rays through said disc, and a lens placed beyond the disc in position to collect the rays passing through the disc and to project the rays onto a screen located in the casing or so arranged as to be visible to the user. This arrangement, together with means for shifting the disc in order to bring successive bands on the disc into the zone of operation of the light and lens, provide means for adapting the idea to instruments operating throughout the range of radio operation.

In the improvement herein disclosed the disc is mounted in a stationary bearing while the lens, or light and lens, are movable radially of the disc. Preferably, the movement is brought about, as in the application above identified, through the medium of the band switch employed instruments of this character.

The invention will be more readily understood by reference to the accompanying drawing, in which, the figure is a perspective view of apparatus adapted to carry out the invention herein disclosed.

In a simple form of apparatus I provide a base 10 on which a variable condenser 11 is mounted, the shaft 12 of which is connected by gears 13 to a tuning dial 14. Preferably, this dial will be composed of a transparent or translucent material and have a series of concentric bands 15, 16, 17 thereon represented by kilocycles, megacycles or station identifications of the various radio sending stations throughout the world. Preferably the indicia is arranged to be readable radially of the disc and will be of relatively minute size. In this manner I am able to provide a large number of station identifications on a small disc.

As a means for projecting the indicia on a screen indicated at 18, preferably carried by the case of the instrument, I utilize an electric light 19, reflector 20 and diffuser 21 all mounted on a slide 22 carried on guides 23 supported by a bracket 24. A lens indicated at 25 is carried

on a support 26 guided on a bracket 27. Movement of the respective light projecting elements, in order to cause the light rays to be projected through different bands on the disc, is brought about through a chain 28 connected to the slide 22 and a chain 29 connected to the slide 26, the respective chains engaging sprockets 30, 31 mounted on a shaft 32 that operates a band switch 33.

In order to maintain the proper focus on the screen, which will be stationary and to maintain the focus at the same point on the screen regardless of movement of the light and lens, it is necessary that the movement of the light source and the lens be slightly different and thus the sprocket 30 for moving the light and associated parts is of greater diameter than the sprocket 31 for moving the lens. This will bring about greater movement of the light than of the lens, and insure that the indicia will always be projected onto the same point on the screen regardless of movement of the light and lens. This enables the use of a screen no wider than the projected matter in any position.

It will be noted that I have shown the indicia on the disc as arranged radially and the light projection apparatus located at a point corresponding to a horizontal line through the axis of rotation of the disc. The advantage from a practical standpoint of an arrangement such as this is in that space may be conserved and a much smaller disc may be used than would be possible by any other arrangement; this for the reason that the angular space required on the disc for any station identification is no greater than the height of the letters or figures used for said identification. If the indicia were arranged to be readable circumferentially of the disc, the space required would be many times greater and require a disc of unwieldy size.

I claim:

1. The combination in a multi-band radio set, of a light source, focusing lens, projection screen, and a transparent rotatable station designating dial suitably mounted in said radio, the periphery of which is disposed between the light and lens, said dial having a plurality of wave band indicia radially spaced from the periphery thereof, means for moving said light source and lens across desired wave bands on said dial whereby to project different radially spaced indicia upon the screen, and means associated with said moving means for maintaining a focus of the lens on a single point on the screen regardless of the movement of the lens.

2. In a multi-band radio set, the combination of a reflector, a light source, a focusing lens and a screen mounted in operable alignment, a rotatable, transparent, station selecting dial operably mounted on said radio and having indicia thereon corresponding to radio stations, said indicia being disposed in a plurality of radially spaced sections, depending upon the wave bands to which they correspond, the outer portion of said dial being disposed between the light and the lens, means operable on said radio for moving said reflector light source and lens across desired wave band indicia on said dial, whereby to project different radially spaced indicia upon the screen, and means associated with said moving means for maintaining a focus of the lens on a single point on the screen regardless of the movement of the lens.
3. In a radio receiving set, the combination with a tuning device having a shaft, of a substantially transparent station selecting disc connected to said shaft for rotation therewith, said disc providing a plurality of circularly arranged, radially spaced indicia, a source of light placed to project rays through said disc past said indicia, a lens positioned to focus said rays, a screen on which said rays are projected to reproduce the indicia on said disc exposed to said light source, means for shifting said light source and lens to project different radially spaced indicia, and means associated with said shifting means for maintaining a focus of the lens on substantially a single point on the screen regardless of the movement of the light and lens.
4. In a multi-band radio receiving set, the combination with a tuning device having a shaft, of a light permeable station selecting disc connected to said shaft for rotation therewith, said disc providing a plurality of circularly arranged radially spaced wave-band indicia, a light source placed to project rays through said disc past said indicia, a lens positioned to focus said rays, a screen on which said rays are projected to reproduce the exposed indicia, means for shifting said lens and light source to project different radially spaced wave-band indicia, and means associated with said shifting means for maintaining a substantially constant focus of the lens regardless of the movement thereof.
5. The combination in a multi-band radio set, of a light source, focusing lens, projecting screen, and a transparent rotatable station designating dial suitably mounted in said radio, the periphery of which is disposed between the light and lens, said dial having a plurality of wave band indicia radially readable and radially spaced from the periphery thereof, means for moving said light source and lens across desired wave bands on said dial whereby to project different radially spaced indicia upon the screen, and means associated with said moving means for maintaining a focus of the lens on a single point on the screen regardless of the movement of the lens.
6. In a radio receiving set, the combination with a tuning device having a shaft, of a substantially transparent station selecting disc connected to said shaft for rotation therewith, said disc providing a plurality of circularly arranged, radially spaced indicia, a source of light placed to project rays through said disc past said indicia, a lens positioned to focus said rays, a screen on which said rays are projected to reproduce the indicia on said disc exposed to said light source, means for shifting said lens to project different radially spaced indicia, and means associated with said light, lens and disc for effecting a focus of the projected matter at a single point on the screen regardless of movement of any one or more thereof.
